FREEMAN F. REYNOLDS, OF BURKE COUNTY, GEORGIA.

Letters Patent No. 60,938, dated January 1, 1867.

IMPROVEMENT IN PLOUGHS.

The Schedule referred to in these Letters Patent and making part of the same.

TO ALL WHOM IT MAY CONCERN:

Be it known that I, FREEMAN F. REYNOLDS, of Burke county, State of Georgia, have invented certain Improvements in Ploughs. I do hereby declare that the following is a full and exact description thereof, reference being had to the accompanying drawing and letters thereon.

Description.

A B, beam four feet long, (wood.) D D, handles three feet six inches long, (wood.) E E, handle-brace, thirty-two inches long, so curved as to give beam A B two inches, and fifteen inches to handles. D D, (iron.) F, handle-rod, sixteen inches long, (iron or wood.) G, helve, fifteen inches long, so curved forward as to bring plough bolt K within eleven inches of nether portion of beam A B, in a rectilinear line, (helve to be of iron,) by virtue of which curve every plough becomes a self-sharpener. S, shoulder in helve. H, helve-brace, twenty inches in length, (iron,) affixed to helve G, by shoulder S, and bolt K, and to beam A B by bolt N. J, detached guide bar, nine inches long, (iron,) affixed to helve G by two lateral bolts, P P. L, wing of Allen or farm plough, without a weld, by virtue of detached guide bar J, and affixed to helve G by bolt K. Every plough used in southern culture can be used on this stock, with or without the guide bar J. M, pivot to prevent side action. R, flange connecting helve G to beam A B.

What I claim as new, and as my invention, and desire to secure Letters Patent for, is—

The adjustment of guide bar J to helve G by bolts P P; the advantage and object of which will be seen in above description, and as incidental to and necessary to the proper running of this stock; also the adjustment of brace H to helve G, by shoulder S and bolt K, and to beam A B by perpendicular bolt N, by virtue of which the ploughs are more easily adjusted to the stock, and less liability of choking, and strength added thereto; the several parts being in combination as specified.

F. F. REYNOLDS.
